UNITED STATES PATENT OFFICE.

LONGLEY LEWIS SAGENDORPH, OF CINCINNATI, OHIO, ASSIGNOR OF ONE-HALF TO CHARLES N. HARDER, OF PHILMONT, NEW YORK.

DESIGN FOR A METALLIC FINISHING-PLATE.

SPECIFICATION forming part of Design No. 19,338, dated October 1, 1889.

Application filed August 17, 1889. Serial No. 321,149. Term of patent 14 years.

To all whom it may concern:

Be it known that I, LONGLEY LEWIS SAGENDORPH, a citizen of the United States, residing at Cincinnati, in the county of Hamilton, 5 State of Ohio, have invented and produced a new and original Design for Metallic Finishing-Plates for Buildings, of which the following is a specification, reference being had to the accompanying drawings, forming a part 10 thereof.

Figure 1 is a plan view of a part of a finishing-plate showing my design, and Fig. 2 is a cross-section taken through one of the cross-grooves in Fig. 1.

15 My design consists of a metallic finishing-plate having figures A, each figure being inclosed by the grooves B, with a circular depression C at the intersection of the grooves, as shown. Each groove B is made up of the

angular portions b and circular portion b', as 20 shown in section, the bottom portion of the circular groove b' being on a plane with the lowest point of the circular depressions C at the intersection of said grooves.

The rectangular figures A may be varied in 25 dimensions to suit the taste of the designer.

What I claim is—

The design for a metallic finishing-plate herein shown and described, the same consisting of figures A inclosed by the grooves B 30 and having the circular depressions C at the intersecting points of said grooves, the latter having the angular portions b and circular portion b', as set forth.

LONGLEY LEWIS SAGENDORPH.
